COSMETIC DEVICE

Thorpe W. Deakers and Lloyd A. Schmucker,
Los Angeles, Calif.

Application July 21, 1939, Serial No. 285,710

3 Claims. (Cl. 132—79)

This invention relates to cosmetic devices of the general character embodied in our joint application for patent filed September 10, 1938, Serial No. 229,342, which has matured into Patent No. 2,193,509 issued March 12, 1940, and wherein is disclosed and claimed a device by which a cosmetic or other preparation can be directly applied to the surface to be treated, without smearing or waste of the preparation.

An object of the present invention is to provide a cosmetic device which is characterized structurally by a minimum number of simply constructed parts forming a compact and inexpensive article, and functionally related in a manner to enable the preparation to be economically used, and naturally and artistically applied by eliminating the use of the fingers as applicators.

Another object of the invention is to provide a cosmetic device in which a receptacle for the preparation, and an applicator carrying closure for the receptacle, are telescopically related in a manner to enable the over-all length of the device to decrease automatically as the preparation is used, so as to accordingly increase the compactness of the device.

A further object of the invention is to provide a cosmetic device in which the telescopically arranged receptacle and closure are diametrically proportioned in a manner for the closure to have a sufficiently snug friction fit on the receptacle in its initial telescoped position on the latter, to be retained connected to the receptacle against accidental separation therefrom, and for the closure to be freely rotatable relative to the receptacle in other telescoped positions of adjustment so as to enable a film of the preparation in the receptacle to be transferred to the applicator in response to a rotary or oscillatory motion of the latter by correspondingly manipulating the closure.

A still further object of the invention is to provide a cosmetic device having means for preventing any of the preparation inadvertently or carelessly deposited from the applicator onto the mouth of the receptacle as the closure is inserted or withdrawn, from being smeared on the outer surface of the receptacle by the closure when applied thereto, the said means also permitting the free flow of air between the telescoped portions of the receptacle and closure in order to prevent the formation of an air pocket which would interfere with relative axial motion between the receptacle and closure.

Another object of the invention is to provide

a cosmetic device in which the applicator is structurally characterized to facilitate the transfer of a film of the preparation thereto from the receptacle.

With these and other objects in view, the invention resides in the combinations and arrangements of elements as set forth in the following specification and particularly pointed out in the appended claims.

10 In the accompanying drawing,

Figure 1 is a central longitudinal sectional view of the cosmetic device in an initially or slightly telescoped position;

15 Figure 2 is a view similar to Figure 1 and showing the cosmetic device in a further telescoped position for transfer of its contents to the applicator;

20 Figure 3 is a view similar to Figure 1, and showing the cosmetic device in its fully telescoped position;

25 Figures 4 and 5 are transverse sectional views taken, respectively, on the lines 4—4 and 5—5 of Figures 1 and 2, respectively.

Referring specifically to the drawing, the invention broadly comprises a receptacle R, and a closure C therefor, carrying an applicator A, all preferably molded of a suitable plastic.

The receptacle R is a tubular, cylindrical body 10, the cylindrical bore 11 of which is of uniform diameter from the one closed end of the body to the other open end or mouth thereof. The body 10 varies in diameter externally with its greatest diameter at and adjacent to its open end as indicated at 12, from which the body 35 tapers to decrease in diameter towards its closed end.

30 The closure C is in the form of a deep cup-shaped cap 13, provided internally with several circumferentially spaced, longitudinally extending ribs 14, and is of a uniform inside diameter except for a portion at its open end which is slightly constricted as indicated at 15. The ribs 14 follow the described internal diametric variation of the closure and co-act at the constricted portion 15 with the greatest diameter 12 of the receptacle to provide a relatively snug or close 40 friction fit between the receptacle and closure in the initial or slightly telescoped position of the two as shown in Figures 1 and 4, all for a purpose to be later described.

45 From the closed end of the closure projects internally thereof a centrally located socket 16 in which is permanently secured by a suitable adhesive, the cylindrical shank or stem 17 of the applicator A, the shank extending from the

closure co-axially with respect thereto, and having on its free end a head 18 of substantially conical form, with respect to which the bottom of the bore 11 of the receptacle is complementary as shown at 19.

The conical surface of the head 18 is provided with a radiating series of grooves 20 or is suitably roughened by serrations, pockets or other means to facilitate the transfer of the contents of the receptacle to the applicator in the operation of the device, which is as follows:

With a predetermined quantity of semi-solid cosmetic or other preparation supplied to the receptacle R, and the closure C applied to the receptacle as shown in Figure 1, the head 18 will just clear the cosmetic, and the portions 12 and 15 of the receptacle and closure will co-act to frictionally retain the closure on the receptacle against loss therefrom.

To transfer cosmetic to the head 18, the closure R is telescoped further onto the receptacle a slight distance which, as shown by Figure 2, is sufficient to frictionally free the closure from the receptacle as the constricted portion 15 of the closure clears the greatest diametered portion 12 of the receptacle. The closure is now freely rotatable so that with the head 18 in contact with the cosmetic, a film of the latter will be transferred to the head. The grooves 20 facilitate this transference of cosmetic as they readily pick up the substance.

The applicator is now withdrawn from the receptacle, and the cosmetic on the head 18 is applied to the lips exactly as desired, without the necessity of using the fingers as applicators for such purpose.

As the cosmetic is used, the closure C is naturally telescoped further onto the receptacle so that the over-all length of the device is reduced to increase its compactness, as shown by Figure 3.

Should any of the cosmetic be transferred from the applicator head 18 to the outer edge of the receptacle R at the mouth of the bore 11 as a result of inaccurate insertion or withdrawal of the applicator, the ribs 14 will prevent the cosmetic from being smeared over the outer surface of the body 10, as the ribs space the internal wall of the closure from the periphery of the body and present only a very small surface circumferentially, to produce a wiping action upon the cosmetic. To further reduce the possibility of smearing the cosmetic on the outer surface of the body, the outer or leading ends of the ribs are tapered to a point as indicated at 14a in Figure 1. Furthermore, the ribs prevent the trapping of

air in the closure and thus eliminate difficulty in applying the closure to the receptacle and removing the closure therefrom.

What is claimed is:

- 5 1. A device of the class described comprising a receptacle; a closure telescopically receiving the receptacle and carrying an applicator insertible into the receptacle for transferring a portion of the latter's contents to the applicator; and means 10 interrupting the circumferential contact of the receptacle and closure at intervals to reduce to a minimum the smearing by the closure on the outer peripheral surface of the receptacle, any of the contents of the latter which is transferred to the mouth of the receptacle from the applicator, by contact of the latter with the receptacle mouth.
- 15 2. A device of the class described comprising a receptacle; a closure telescopically receiving the receptacle and carrying an applicator insertible into the receptacle for transferring a portion of the latter's contents to the applicator; and a plurality of longitudinally extending ribs on the internal wall of the closure, spacing such wall from the outer wall of the receptacle and operable to reduce to a minimum, the smearing of any of the receptacle's contents from the mouth thereof onto the outer surface of the receptacle by the closure during telescoping movement thereof.
- 25 3. A cosmetic device comprising a tubular receptacle member closed at one end and open at the other for receiving and holding a supply of plastic cosmetic material, the exterior of said member tapering inwardly from the open end thereof, a cover comprising an elongated tubular member also closed at one end and open at the other end, the internal bore of said cover member being of a diameter sufficient to freely telescope about the largest exterior diameter of said receptacle member, an applicator fixed upon the closed end of said cover member and extending within said cover member toward the open end thereof to engage and remove portions of the contents of the receptacle when the cover is telescoped thereon, said cover member having a constriction of its bore immediately adjacent the open end thereof to engage the large end of said receptacle to thereby prevent accidental removal of the cover while permitting free rotational and longitudinal movement of said cover and applicator when the said receptacle end is telescoped within said cover member at all other positions of the cover on the receptacle.
